[57] ABSTRACT

A trap switch for a burglar alarm system consists of a base member adapted to be mounted on a fixed body and a movable member adapted to be connected to a movable member by an elongated flexible wire. The base member has a pair of fixed contacts biased toward one another with an access slot in the base member housing disposed in a region between the fixed contacts. The movable member has an extending insulation stab portion carrying insulated conductive surfaces on its opposite sides. The extending stab can be pressed between the fixed contacts of the base member and each contact engages one of the conducting stab surfaces. An extending wire is mechanically connected at its ends to the conductive surfaces. A continuity circuit is connected in series with the fixed contacts, and can be either normally open or normally closed depending on whether the elongated wire is conductively connected between the conductive surfaces.

TRAP SWITCH WITH ELONGATED MOUNTING WIRE FOR COMPLETING CONTINUITY CIRCUIT

BACKGROUND OF THE INVENTION

This invention relates to switch structures, and more particularly relates to a trap switch for use in a burglar alarm system wherein the switch has an elongated wire serving as the operator of the switch. It is known to provide two-piece switches for burglar alarm systems in which a base piece carrying spaced contacts pressed toward engagement with one another cooperates with a movable piece having an elongated insulated stab. The stab is normally between the spaced contacts and holds them apart so that the circuit between the contacts is normally open. The movable part then has a wire or strap, or the like connected thereto and connected to a movable structure, such as a window, venetian blind, drape, gate, or the like, whose movement is to be monitored. The movement of such a body will move the movable member away from the fixed member so that the stab is withdrawn from between the spaced contacts, thus allowing them to close and actuate appropriate circuits. Note, however, that the switch cannot be used in a normally closed circuit which is to be opened upon removal of the stab without substantial modification of the structure.

BRIEF SUMMARY OF THE INVENTION

The principle of the present invention is to provide a novel trap switch with a pair of removable conductive surfaces on the conventional insulation stab, and to thereafter use the device actuating wire to make electrical connection between these surfaces when it is desired to use the switch in a normally closed circuit. When the conductive surfaces are removed, the insulation stab will operate as in the past. However, by the simple modification of using a conductor for the actuating wire, and connecting this conductor between the conductive surfaces, and then bending the contact strips of the fixed housing so that they do not make contact when the stab is withdrawn, the switch can be used in a normally closed circuit.

BRIEF DESCRIPTION OF THE DRAWINGS

FIG. 1 is a top view of the novel switch of the invention.

FIG. 2 is a side elevation of the switch of FIG. 1 with the movable member partly withdrawn to show the three-component stab of the invention.

FIG. 3 is an exploded perspective view of the fixed member of the switch of FIGS. 1 and 2.

FIG. 4 is an exploded perspective view of the movable member of the switch of FIGS. 1 and 2.

FIG. 5 is a cross-sectional view of FIG. 1 taken across the section line 5-5 in FIG. 1 and showing the fixed and movable members disengaged for clarity.

DETAILED DESCRIPTION OF THE DRAWINGS

Referring now to the drawings and particularly FIGS. 1 and 2, there is shown what will hereinafter be referred to as the fixed switch member 10 and movable switch member 11. It will be apparent that these roles could be reversed and, more broadly, it is only necessary that there be motion of one relative to the other to cause switch operation. A main continuity circuit includes conductors 12 and 13 which are connected to terminals in fixed member 10, and an actuating wire 14

is connected to movable member 11. In its most common application, the fixed member 10 will be secured to a fixed body, such as a windowsill, while the wire 14 will be connected to a movable member, such as a venetian blind, such that the movable member 11 will be withdrawn from member 10 by the operation of the venetian blind.

FIGS. 3 and 5 show the details of construction of fixed member 10. Thus, member 10 includes a molded base portion 20 enclosed by a molded cover 21. Base 20 contains integral extensions 22 and 23 at its ends (pedestal 22 is not visible in FIG. 5) which pedestals contain through-openings which terminate in countersunk nut openings in the bottom of base 20. Cover 21 has openings 24 and 25 aligned with pedestals 22 and 23 so that securing screws 26 and 27, which hold cover 21 on base 20, can be inserted into pedestals 22 and 23. Nuts 28 and 29 (FIG. 1), which are contained in the countersunk openings on the bottom of base 20, threadably receive screws 26 and 27 to hold the cover 21 in position.

Base 20 is further provided with through-openings 30 and 31 which receive mounting screws (32 and 33 in FIG. 1) for holding the fixed member 10 in its desired position. Note that the cover 21 must be raised (and thus the movable member 11 thereon) to gain access to mounting screws 32 and 33 so that the switch will be operated if one attempts to bodily remove the switch. Base 20 is also provided with integral sidewall portions 34 and 35 which contain between them pedestals 36 and 37. Pedestals 36 and 37 contain openings 38 and 39 respectively which extend to countersunk openings 40 and 41, respectively (FIG. 5). A pair of bent phosphor bronze contact springs 42 and 43 are then provided with openings 44 and 45, respectively, at one end and generally U-shaped bends at the other end and are connected to pedestals 36 and 37 by screws 46 and 47, respectively. Thus, screws 46 and 47 extend through the openings 44 and 45 in springs 42 and 43, respectively, and then through openings 38 and 39, respectively, and then are secured by nuts 48 and 49, respectively. Note that the U-shaped bent portions of contact springs 42 and 43 face one another, and could normally engage one another if the U-shaped portions are bent sufficiently open.

In order to allow access to the region between contacts 42 and 43, the cover 21 contains a slot 50. Cover 21 also contains slots 51 and 52 to allow leads 12 and 13 to enter the fixed member 10. Leads 12 and 13 are then connected to contacts 42 and 43 by being secured under the heads of screws 46 and 47, respectively.

The movable switch member 11 is shown in detail in FIGS. 4 and 5. Thus, it includes molded base 60 and molded cover 61. Base 60 contains integral cylindrical posts 62 and 63 which support the cover 61, and further contains openings 64 and 65. The bottom of base 60 contains four countersunk openings aligned with through-openings 66 and 67 in posts 62 and 63, respectively, and with openings 64 and 65. These four countersunk openings receive nuts 68, 69, 70 and 71. A square opening 72 is formed in base 60 and receives a central stab member 73 of insulation material. Stab 73 may be secured to the sidewalls of opening 72, or may be integrally molded therewith.

Two L-shaped brass contacts 74 and 75 are then provided with openings 76 and 77 and are inserted through opening 72 and along either side of insulation stab 73.

Note that contacts 74 and 75 are normally insulated from one another by stab 73. Screws 78 and 79 inserted through openings 76 and 77, respectively, and received by nuts 69 and 70, respectively, hold the contacts 74 and 75 in position.

Elongated wire 14, which may be an insulation covered copper wire, has its terminal ends connected beneath the heads of screws 74 and 75, with these ends inserted through opening 80 in housing 61. Note that when wire 14 is an insulated conductor, contacts 74 and 75 are electrically connected to one another. In some applications, e.g., with contacts 74 and 75 removed wire 14 does not make an electrical connection between contacts 74 and 75.

The cover 61 is then provided with openings 81 and 82 which receive mounting screws 83 and 84, respectively, which are captured by nuts 68 and 71, respectively, to hold the cover 61 on base 60.

The operation of the switch can now be understood from FIGS. 2 and 5. If the switch is to be used in a normally conducting circuit, or one which is continuous between conductors 12 and 13 with movable member 11 in its closed position (with stab 73 and its conductive members 74 and 75 in the fully inserted position between contacts 42 and 43), then the contacts 74 and 75 are electrically connected by wire 14 and contacts 42 and 43 are bent so that they do not touch when in their unflexed position. Movable member 11 is then placed in its fully connected position by inserting stab 73 (and conductors 74 and 75) through opening 50 in housing 21 and between contacts 42 and 43. There is a relatively light spring contact pressure between contacts 42 and 74 and contacts 43 and 75 to define a continuous circuit from wire 12, terminal screw 46, contact 42, contact 74, wire 14, contact 75, contact 43, terminal screw 47, and wire 13.

The movement of the member mechanically connected to wire 14 easily lifts the switch member 11 away from fixed member 10 against the light spring pressure of contacts 42 and 43 until there is disengagement of contacts 42 and 43 from contacts 74 and 75, respectively. This opens the circuit between wires 12 and 13 to initiate a suitable alarm.

In order to use the same assemblage in a normally nonconducting alarm system, the only change needed is that the contacts 74 and 75 are removed. At the same time, the phosphor bronze contacts 42 and 43 are bent more open to a position where they normally engage one another. In this mode of operation, insertion of insulation stab 73 between contacts 42 and 43 simply spreads contacts 42 and 43 away from one another and out of contact. Therefore, there is not a continuous circuit between wires 12 and 13. However, when member 11 is moved and the stab moves away from between contacts 42 and 43, they will close to complete a circuit between wires 12 and 13 to actuate a suitable alarm.

Although this invention has been described with respect to preferred embodiments, it should be understood that many variations and modifications will now be obvious to those skilled in the art, and therefore, the scope of this invention is limited not by the specific disclosure herein, but only by the appended claims.

The embodiments of the invention in which an exclusive privilege or property is claimed are defined as follows:

1. A trap switch for a burglar alarm system; said trap switch comprising a first switch member including a

first closed housing and a second switch member including a second closed housing; said first switch member including mounting means for mounting said first switch member to a first body; said second switch member including means for mechanically connecting said second switch member to a second body which is relatively movable with respect to said first body; said first switch member including a first pair of spaced contact members which face one another; respective terminal means connected with each of said first pair of contact members and disposed within said first closed housing; an opening in one wall of said first closed housing; said opening disposed adjacent to the area which includes said first pair of spaced contact members; said second switch member including a second pair of spaced contact members secured to said second switch member; respective terminal means connected with each of said second pair of spaced contact members and disposed within said second closed housing; an opening in one wall of said second closed housing; said second pair of spaced contact members extending through said opening in said second closed housing; an insulation member disposed between said second pair of contact members; said insulation member and said second pair of contact members defining a projecting stab; said projecting stab extending through said opening in one wall of said first closed housing and between said first pair of spaced contact members, with said first pair of contact members respectively engaging said second pair of contact members; said one wall of said first housing being disposed over said one wall of said second housing, thereby to cover the said openings in said housings.

2. The trap switch of claim 1 wherein said first pair of contact members are spring biased normally to engage one another, and wherein said second pair of contact members are removable to define insulation surfaces for said stab, whereby a circuit is closed between said terminal means of said first pair of contact members only when said second switch member is moved to retract said stab from between said first pair of contact members.

3. The trap switch of claim 2 wherein said first pair of contact members are elastically deformable to a condition in which they are normally engaged when said stab is removed.

4. The trap switch of claim 1 wherein said first pair of contact members are spring biased normally to be out of contact with respect to one another, and which includes conductor means connected between said terminal means of said second pair of contact members for electrically connecting said second pair of contact members, whereby, when said stab is in said position between said first pair of contact members, there is a closed circuit between said terminal means of said first pair of contact members, and whereby removal of said stab by movement of said second switch member opens said closed circuit.

5. The trap switch of claim 4 wherein said first pair of contact members of a contact spring material is deformable to a condition wherein said first pair of contact members are normally out of engagement with one another.

6. The trap switch of claim 4 wherein said means for mechanically connecting said second switch member includes a wire having its ends at least mechanically connected respectively to said terminal means of said second pair of contact members.

7. The trap switch of claim 6, wherein said wire is at least partly insulation covered.
8. The trap switch of claim 1 wherein said means for mounting said first switch member is disposed within said first housing.
9. The trap switch of claim 1 wherein said means for mechanically connecting said second switch member

includes a wire having its ends at least mechanically connected respectively to said terminal means of said second pair of contact members.

10. The trap switch of claim 1, further comprising means electrically connecting said terminal means for said second pair of contact members.
